UNITED STATES PATENT OFFICE.

WILLIAM RICHEY McMURRAY, OF BELFAST, IRELAND.

THREAD-DRAWING MACHINE.

1,237,927.

Specification of Letters Patent. Patented Aug. 21, 1917.

Application filed December 28, 1915. Serial No. 68,999.

To all whom it may concern:

Be it known that I, WILLIAM RICHEY McMURRAY, a subject of the King of Great Britain and Ireland, residing at Belfast, Ireland, have invented certain new and useful Improvements in and relating to Thread-Drawing Machines, of which the following is a specification.

This invention relates to machines for removing threads from fabric preparatory to the production of open work effects as required for "shire" and the like sewing and it specially relates to machines of this class in which the threads, or portions of the threads, to be removed are pushed downward and the portions projecting below the fabric then cut off.

As is usual in the known types of thread removing machines, the threads, which are to be removed, are pushed downward by means of a vertically reciprocating serrated edged pusher and I, preferably, employ the usual needle bar mechanism of a sewing machine for operating same.

The invention consists in providing improved presser foot and fabric holding and stretching devices, consisting of a cloth plate having one or more upward projections, for example, bars or rails, on each side of the cloth plate and lying in the direction of the feed of the fabric and adapted to engage a corresponding recess or recesses at the underside of the presser foot. Or the recesses may be provided in the cloth plate and the projections for engagement with the recesses be provided on the underside of the presser foot. In either case, the arrangement is such that, on the pressing downward of the presser foot, the fabric underneath is held

and stretched during the thread cutting operation, owing to the fabric being gripped between the projections and the recesses in the cloth plate and presser foot respectively; or, in the presser foot and cloth plate, respectively, as the case may be. I also provide an improved thread cutter which consists of a swinging or oscillating knife suitably supported underneath the cloth plate and which can be operated by link and lever or equivalent mechanism actuated from one or other of the ordinary oscillating feed shafts of a sewing machine, the oscillating knife being thereby moved across the underside of a hole in the cloth plate through which the threads are pushed by the vertically reciprocating pusher. Preferably, the

underside of the cloth plate would be so made, and the oscillating knife so made and set, that the latter would bear more or less resiliently against the underside of the cloth plate in order to insure the knife cutting the threads as closely as possible to the underside of the fabric.

If desired I may provide means for drawing off the fluff or cuttings of the threads from below the machine.

In order that the invention may be clearly understood I have hereunto appended three explanatory sheets of drawings whereon I have shown, by way of example, a thread removing machine made in accordance with the invention.

Figure 1 is a side elevation of the machine, portions of the base and rocking shaft mechanism being removed to clearly show the thread cutter and its connections.

Fig. 2 is a plan view of the machine with the head and presser foot and cloth plate removed to show the thread cutter and cloth feeding mechanism.

Fig. 3 is a front end elevation of the machine.

Figs. 4, 5 and 6 are detail views showing the cloth plate, presser foot, and thread cutter, in position.

Figs. 7, 8 and 9 are detail views showing an alternative arrangement to that shown at Figs. 1 to 6.

Fig. 10 is a detail view corresponding to Fig. 5 but showing projecting bars or rails on the presser foot engaging recesses or grooves in the work plate.

On the drawings the same reference letters, wherever repeated, indicate the same parts.

Referring to the drawings:

The machine may be made with operative mechanism similar to that of an ordinary hem-stitch sewing machine or it may be constituted by a hemstitch sewing machine whose parts are altered to suit. The machine shown is a hem-stitch sewing machine of the Wheeler & Wilson type but with the shuttle mechanism removed and instead of having a needle, a serrated edged pusher is attached to the needle bar. The dotted lines in the arm of the machine indicate the usual sewing machine mechanism for operating the needle bar while the usual feed shaft, drop feed motion and rock bar feed shaft are shown under the bed plate of the machine.

2

Each time the needle bar is moved downward the pusher *a* pushes or forces the threads downward through a hole *b*³ in the cloth plate *b* of the machine, whereupon the threads are cut and removed by a swinging or oscillating knife *c* which is adjustably supported on a lever *c*¹ fulcrumed at *c*² and oscillated from the rock bar *d* of the drop feed motion of the machine through the medium of a lever *d*¹ and link *d*² connected to the lower end of the lever *c*¹. The movement could also, if desired, be obtained from the rock bar feed shaft *e* of the machine, as shown at Figs. 7, 8 and 9. The oscillating knife *c* being, in this case, supported on lever *c*¹ which is fulcrumed at *c*² and oscillated from the rock bar feed shaft *e* by means of a depending arm *d*¹ connected by a link *d*² with the lower end of the lever *c*¹. 10 In either case the knife *c* is reciprocated to and fro under the cloth plate *b* which is preferably curved to suit the curved path described by the knife and in order to bring the knife, as near as possible to the underside of the cloth on the cloth plate, it may be so set that its cutting edge bears either stiffly or resiliently against the curved underside of the cloth plate. The cloth is held and stretched, during the cutting of the threads, by the coöperation of the presser foot and cloth plate. For this purpose the presser foot *f* of the machine is provided with two recesses *f*¹ and *f*² adapted to engage corresponding projecting bars or rails *b*¹ and *b*², see Fig. 4, on the upper side of the cloth plate *b* so that, when the foot is pressed down, the fabric between it and the cloth plate *b* will be securely held and stretched by the clamping action of the recesses and projections on the presser foot and cloth plate respectively. Fig. 10 shows the projections on the presser foot and the recesses in the cloth plate. This clamping action entirely prevents side play of the cloth or fabric during the cutting of the threads and insures a clean and regular "shiring" of the cloth or fabric. 15 20 25 30 35 40 45

The fluff or cuttings of the threads may be

drawn away from below the machine by means of an air suction apparatus arranged so as to draw the fluff into a suitable duct, indicated by the dotted lines at *h*, leading to a box or receiver wherein the fluff can be collected. The suction apparatus which may be in the form of an air pump may be operated from, or by, the machine mechanism or it may be independently driven. If desired, a number of machines may be connected to a common extractor. 50 55

Having now fully described my invention what I claim and desire to secure by Letters Patent is:—

1. A machine for removing threads from fabric having a cloth plate with a hole therein, a pusher or displacing threads from the fabric and pushing them through said hole, means for operating the pusher, an oscillating cutting knife working across the underside of the cloth plate below the hole therein and so as to cut the threads displaced by the pusher, and means comprising a presser foot with recesses on the underside thereof and a cloth plate with projections on the upper side thereof, the presser foot and cloth plate being adapted to coöperate to hold and stretch the fabric. 60 65 70 75

2. A machine for removing threads from fabric, having oscillating feed shafts, a cloth plate with a hole therein, a pusher for displacing threads from the fabric and pushing them through said hole, means for operating the pusher, an oscillating cutting knife working across the underside of the cloth plate below the hole therein and so as to cut the threads displaced by the pusher, link and lever mechanism, for operating the knife, actuated from one of the oscillating feed shafts, and means for holding and stretching the fabric during the thread cutting operation. 80 85 90

In testimony whereof I affix my signature in presence of two witnesses.

WILLIAM RICHEY McMURRAY.
